UNITED STATES PATENT OFFICE

GEORG KIRKEGAARD, OF NEW YORK, N. Y., ASSIGNOR TO IMPERIAL STOPPER COMPANY,
A CORPORATION OF MAINE.

BOTTLE-STOPPER.

No. 890,910.

Specification of Letters Patent. Patented June 16, 1908.

Application filed September 10, 1907. Serial No. 392,181.

To all whom it may concern:

Be it known that I, GEORG KIRKEGAARD, a citizen of the United States, residing at the city of New York, in the borough of Brooklyn and State of New York, have invented certain new and useful Improvements in Bottle-Stoppers, of which the following is a full, clear, and exact description.

This invention relates to stoppers for bottles and other similar vessels, and has special reference to that type of stopper comprising a metallic cap carrying inside thereof a packing of cork or other suitable material, and having a depending edge or rim adapted to engage a shoulder formed exteriorly around the mouth of the vessel.

The object of the present invention is to provide a stopper of this general character of such construction and application to the bottle that it will maintain the seal of the bottle against the most excessive internal pressures, notwithstanding the fact that the metal of which the cap is made may be very thin. In other words, the holding devices are of such efficiency from their mere form that the weight or stiffness of the metal may be less depended upon than in other constructions to hold the stopper in place.

The invention consists of the specific construction hereinafter described and claimed.

In the accompanying drawing: Figure 1 is a plan of the metallic cap before it is applied to the bottle; Fig. 2 is a side elevation of the same; Fig. 3 is a central section of the stopper resting upon the bottle and before it is fastened thereto; Fig. 4 is a section of the stopper and bottle in the sealed condition; Fig. 5 is a side elevation of the sealed bottle neck; Fig. 6 is a bottom plan of the stopper when in its sealing condition but with the bottle removed; and Fig. 7 is a view similar to Fig. 1, but with the disk portion of the cap removed, and illustrating a modification of the invention.

The metallic cap comprises the usual disk portion 1, a cylindrical depending wall 2, and a flaring edge or rim 3. Within the cylindrical wall is inclosed the usual packing disk of cork or other similar material 4. The bottle 5 is provided with the now well-known exterior annular, inwardly inclined shoulder 6, near its mouth. The flaring rim is provided with the formations which are utilized to secure the cap to the bottle. Upon this flaring rim between the extreme edge and the

line where it bends from the cylindrical wall, are formed a series of inward depressions 7, or embossings, which form downward or inward projections 8, on the under side of the rim. Each one of these depressions 7 is continued in a radial direction to the extreme edge 9, of the rim, forming thereby a series of radial grooves 10, in the upper surface of the rim, and a corresponding series of radial ribs or projections 11, on the under side of the rim, and which are narrower than the depressions 7.

In lieu of the depressions and projections 7 and 8, I may provide a continuous annular depression or groove 12, as seen in the modification Fig. 7 and extend from this groove the same radial depressions 10 at suitable intervals around the edge. In fixing this cap or stopper upon the bottle it is first placed over the neck of a bottle, as shown in Fig. 3, then by suitable means the disk 1 is forced downward to compress the packing material 4, as shown in Fig. 4, and then by any suitable means the flaring rim 3 is forced downward and inward so as to be substantially in line with the cylindrical wall 2, as seen in Fig. 4. This can best be done by means of a sealing tool comprising a ring having an internal diameter that will just fit over the cylindrical wall 2. This ring is then forced straight downward causing the rim to bend gradually downward and inward, the radial grooves 10 meanwhile closing up to allow the edge of the rim to assume the necessarily smaller diameter without irregular crimping. This downward and inward movement of the flaring rim throws the projections 8 under the shoulder 6 of the bottle, and thus locks the cap in the position shown in Figs. 4 and 5. This lock is made especially effective and strong because each of the projections 8 is backed up or reinforced by the pinched-up sides of the grooves 10. If the metal of which the cap is made is sufficiently thick and stiff, the projections 8 alone would ordinarily hold the stopper in place, but by providing the reinforcing means 10-11 back of each projection 8, I am able to use much lighter material for the cap and correspondingly cheapen the manufacture. How each of the projections 8 is backed up by the projection 11 is clearly shown in Fig. 6.

The modified form shown in Fig. 7 affords a continuous holding device in engagement with the shoulder 6, that is to say, the bead 110

on the under side of the rim formed by the groove 12 annularly engages the shoulder 6 and its hold thereon is reinforced by the radial projections formed by the grooves 10 which are also compressed together when the flaring edge is bent into cylindrical form.

Having described my invention, what I claim, is:

A bottle stopper comprising a cap containing a packing disk and having a flaring rim provided with indentations forming holding lugs and located wholly within the borders of

said rim, the rim also having radial grooves or folds extending from said indentations to the other edge of the rim and being narrower than the indentations themselves, substantially as described.

In witness whereof, I subscribe my signature, in the presence of two witnesses.

GEORG KIRKEGAARD.
